(57) CLAIM

The ornamental design for a clip of writing instrument, as shown and described.

DESCRIPTION

FIG. 1 is a perspective view of the clip of writing instrument showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken line showing of FIGS. 1-7 is for illustrative purposes only and forms no part of the claimed design.
